UNITED STATES PATENT OFFICE.

WILLIAM P. HILL, OF SOMERVILLE, MASSACHUSETTS.

CURTAIN-POLE RING.

SPECIFICATION forming part of Letters Patent No. 361,873, dated April 26, 1887.

Application filed December 14, 1886. Serial No. 221,574. (No model.)

To all whom it may concern:

Be it known that I, WILLIAM P. HILL, a citizen of the United States, residing at Somerville, in the county of Middlesex and State 5 of Massachusetts, have invented certain Improvements in Curtain-Pole Rings, of which the following is a full, clear, and exact description, reference being had to the accompanying drawings, making part of this specification, in which—

Figure 1 is a front elevation of a curtain or portière suspended from a curtain-pole by means of my improved curtain-pole rings. Fig. 2 is a side elevation of one of my improved 15 curtain-pole rings. Fig. 3 is a sectional elevation of the same on the line xx of Fig. 2. Fig. 4 is a side elevation of one of my rings having a friction wheel or roller applied thereto. Fig. 5 is a sectional elevation of the same 20 on the line yy of Fig. 4. Fig. 6 is a side elevation of a ring having a friction wheel or roll of slightly-different construction and arrangement applied thereto. Fig. 7 is a sectional elevation of the same on the line zz of Fig. 6.

The ordinary curtain-pole rings are objectionable for the reason that in drawing aside the suspended portière or drapery the rings, which are connected at the bottom with the said drapery and which bear only at the top 25 upon the pole, are swung out of their normal vertical planes and are often brought into a position to bind upon the pole, both at the top and bottom, which seriously interferes with the free sliding of the said rings upon the pole 30 and prevents the drapery from being drawn back at the top as desired.

My invention has for its object to overcome this difficulty; and it consists in the combination, with a curtain-pole ring, of a swinging 40 semicircular bail or hanger adapted to be connected with the curtain or drapery to be suspended and extending up partially around and close to the outer periphery of the ring, and having its extremities pivoted to said ring 45 at points on opposite sides of the same on a horizontal line passing through or near the center of the ring when in position upon the pole, the arrangement being such that the force employed to move the ring along the 50 pole when the curtain or drapery is drawn to one side is applied through the said pivoted

bail in such a manner as to always maintain the ring in or nearly in a vertical position while being slid along the pole, and all liability of its binding thereon is thus entirely avoided, 55 and its free movement in either direction at all times insured.

In the said drawings, A represents a curtain-pole ring, which may be formed of metal, wood, or other suitable material. To the outside of this ring upon opposite sides is pivoted at points a , on a horizontal line passing through or near the center of the ring when in position upon the pole, and in a vertical plane passing through the entire circumference of the 65 ring, a swinging semicircular bail or hanger, B, preferably composed of wire and having a central eye or socket, c , at its bottom for the reception of the ordinary hook which is attached to the upper edge of the portière or 70 other drapery D suspended from the rings A, which are adapted to slide upon the pole G, the latter being supported, as usual, by brackets d , as seen in Fig. 1. When the drapery D is drawn to one side or the other, the bails or 75 hangers B are swung on their pivots a out of their usual vertical positions, while the rings A remain in vertical or nearly vertical planes, as seen in Fig. 1, the draft or force exerted to slide the rings along the pole being thus applied in such manner as to keep the rings always in or nearly in a vertical position as they are slid along the pole, thereby effectually preventing them from binding on the same, as would be liable to occur if the rings themselves were drawn at an angle, as heretofore, 80 and consequently, where my improved rings are employed, no difficulty is experienced in drawing the drapery at the top along the pole in either direction when desired, much trouble 85 and annoyance being thus avoided.

To still further facilitate the free sliding movement of the ring A along the pole G, I sometimes provide the said ring at its top with an anti-friction roll, H, which is preferably made 95 in the form of a hollow sleeve, like that of a buckle, as seen in Figs. 4 and 5, and is of such diameter and so arranged as to form a portion of both the inner and outer periphery of the ring, the part f of the ring, upon which the 100 sleeve is fitted, being made straight to enable it to rotate freely thereon. If preferred, a sec-

tion of the ring may be entirely removed and a space thus formed for the reception of a wheel or solid roll, as seen in Figs. 6 and 7, which revolves on a pin, *g*, and forms, like the 5 tubular roll in Figs. 4 and 5, a portion of the inner and outer periphery of the ring. These anti-friction rolls, however, form no part of my invention, as they have been employed in connection with curtain-pole rings in many 10 different ways; hence I lay no claim to an anti-friction roll applied to a curtain-pole ring.

What I claim as my invention, and desire to secure by Letters Patent, is—

The combination, with a curtain-pole ring, 15 of a swinging semicircular bail or hanger, *B*, adapted to be connected with the curtain or drapery to be suspended and extending up

partially around and close to the outer periphery of the ring, and having its extremities pivoted to said ring at points *a* on opposite 20 sides of the same on a horizontal line passing through or near the center of the ring when in position upon the pole, whereby the ring is maintained in a vertical or nearly vertical position while being slid along the pole in 25 either direction, substantially as and for the purpose set forth.

Witness my hand this 10th day of December, A. D. 1886.

WILLIAM P. HILL.

In presence of—

P. E. TESCHEMACHER,
EDWIN F. EDGETT.
